UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed January 26, 1924. Serial No. 688,658.

This invention relates to internal combustion engines, more particularly to the valve mechanism thereof, and it has for an object to provide improved apparatus whereby the 5 valves of large internal combustion engines may be cooled by the circulation therethrough of an appropriate fluid medium.

The invention is particularly applicable to high speed, heavy duty engines such as 10 are used in the propulsion of aircraft. It has been illustrated with reference to an engine of the dual valve type, in which each cylinder is provided with exhaust and intake valves arranged in pairs, the valves of 15 each pair being adapted for operation in unison, but it is to be understood that the invention is not so limited but is capable of application to engines of other types, having different valve arrangements.

It is not uncommon for the exhaust valves 20 of large aircraft engines to operate at temperatures approaching white heat, and serious troubles in operation, such as pre-ignition, and cracking, warping and burning 25 of the valves frequently result from this cause. It has been heretofore suggested that such difficulties might be obviated by providing these engines with hollow valves and stems, and maintaining therethrough a 30 circulation of suitable cooling fluid, such as oil. It is one of the objects of this invention to provide means for insuring a direct and positive flow of cooling fluid through each of the engine valves of such an engine 35 during a portion of the valve cycle.

Another object is to provide simple and efficient means, directly associated with the valve operating mechanism for positively forcing a quantity of cooling oil through 40 each valve on every stroke thereof.

Another object is to provide positive valve means, operable in connection with the valve operating mechanism, to prevent a back flow of the cooling fluid.

Other objects of the invention will appear 45 from the following description taken in connection with the drawings, which form a part of this specification, and in which:

Fig. 1 is a transverse vertical section 50 through a part of an internal combustion engine, illustrating the application of this invention thereto;

Fig. 2 is a longitudinal vertical section substantially on the line 2—2 of Fig. 1, the

valve actuating mechanism being illustrated 55 in a different position;

Fig. 3 is a horizontal section substantially on the line 3—3 of Figs. 1 and 2, and

Fig. 4 is a vertical section substantially 60 on the line 4—4 of Fig. 2.

Referring to the drawing, at 10 is illustrated a portion of an internal combustion engine having a cylinder 11 and provided with a head casting 12. The head casting 12 contains ports 13, located over each of 65 the cylinders 11, and connecting with passages 14, for the intake of fuel to and the exhaust of burned gases from the cylinders. Each of the ports 13 defines a valve seat 16, adapted to cooperate with a poppet valve 70 17 in the usual manner. The head casting 12 also contains suitable cooling passages 18, through which water from the engine cooling system is circulated in the well known manner, and is preferably provided with a 75 suitable dust and oil tight cover 15. The casting 12 and its associated parts, is mounted in the ordinary way on the engine block which contains the cylinders 11, and is secured thereto in any appropriate manner, as by stud bolts 19.

The valves 17 may be of any well known type. They have been illustrated as arranged in pairs, two exhaust valves and two intake valves being placed side by side and comprising sets which are adapted for operation in unison, to secure the maximum valve opening for each cylinder, as will be readily understood. The valves 17 are formed with hollow heads 21 and with communicating 80 hollow stems 22. The stems 22 are mounted in suitable guides 23 rigidly supported in the head casting 12 in any well known manner, as by being pressed into holes drilled in the bosses 24, and are arranged in alignment with the ports 13, so that the valves 17 may cooperate with the valve seats 16 to control the flow of gases through said 85 ports 13.

Secured to each of the valve stems 22 at its upper end is a collar 26, having a horizontally disposed flange forming an abutment on which the valve return means exerts its pressure to seat the valve. As 100 shown, this valve return means comprises a plurality of compression springs 27, arranged about each of the valve stems 22, and bearing at their upper ends on the abut- 105

ments 26 and at their lower ends on an abutment 28. The abutment 28 is an annular member mounted on the head casting 12 to surround each of the valve guides 23. This annulus carries a number of guide pins 29, one within each of the springs 27, by means of which lateral flexure thereof is prevented. The abutment 26 has also a down-turned peripheral flange, and is provided with holes 31 for the passage of the upper ends of the pins 29. This valve return means urges the valve stem 22 and the valve 17 upwardly against the valve seat 16 in a manner well known in the present art. The valves 17 of each pair are connected by a yoke member 33, mounted to extend between the extremities of the valve stems 22. The yoke member 33 is provided at its ends with tappet members 36 having shank portions seated in holes 34 formed in the ends of the yoke member. The tappet members 36 have enlarged heads 37, forming shoulders 38 for the reception of shims 39, by means of which adjustment of the valve tappet clearance may be effected in an obvious manner, and they are retained in the yoke members by nuts 40. Each yoke member 33 is also formed with an integral downwardly disposed guide member 41 at its center, this guide member 41 forming a plunger adapted to reciprocate in a cylinder 42 which has a closed lower end.

The cylinder 42 is supported in an opening 43 provided in a lug 44 of a bracket 46, which bracket is secured to the head 12 as by bolts 47. The cylinder 42 may be secured in the opening 43 in any convenient manner, as by being pressed therein.

The bracket 46 is adapted to support a cam shaft 48 by means of which the yoke members 33 are actuated. For this purpose the bracket is adapted to carry bearings 49 in which the cam shaft 48 is journaled, there being a bearing and a supporting bracket 45 therefor intermediate the valves of each cylinder. The bearings 49 are preferably formed in two parts and are secured in the bracket in a well known manner as by means of the removable cap 51, as clearly shown in Fig. 4.

The cam shaft 48 is formed with suitable cams 52, each adapted to engage and operate one of the yoke members 33. The cam shaft is driven from the engine in any appropriate manner, as by means of gearing (not shown). It is hollow and is connected to some suitable source of cooling fluid under pressure such as a pump (not shown). This cooling fluid is preferably lubricating oil, such as is used for the lubrication of the engine, but it is to be understood that other cooling fluids, such as water, for example, may be used. Between each pair of valves may be located a suitable support, such as the post 56 mounted on the stud 57 in the

head 12, adapted to support a cross head 58 having guide faces 59. These are slidably engaged by similar guide faces on the yoke members 33 to prevent turning of the latter about the plunger 41.

The operation of the engine valves from the engine will be obvious. As the cam shaft 48 is rotated in timed relation to the engine the cams 52 successively engage the various yoke members 33 and depress them, thus opening the valves 17 by means of the contact of the tappets 36 with the stems 22, against the pressure of the springs 27. As the operation of engine valves in this manner is well known in the art to which this invention relates, further description of this operation is believed to be unnecessary.

The hollow cam shaft 48 is provided at each of its bearings with suitable metering ports 61, each of which communicates with the interior of the shaft. These metering ports 61 are adapted to register during a portion of each revolution of the shaft with a metering slot 62, formed in the lower half of the bearing 49. This metering slot 62 communicates, by means of a passage 63 formed in the bracket 46, with a horizontal passage 64 in the lower part thereof, and which may be conveniently formed as a slot cut in its base. The passage 64 extends diagonally across the base of the bracket 46 and communicates with the interior of the cylinder 42 through a port 66. It will be evident that when the port 61 registers with the slot 62, fluid under pressure from the interior of the hollow cam shaft 48 is admitted by way of passages 63 and 64, and port 66, to the cylinder 42 beneath the plunger 41 therein.

The plunger 41 has a central vertical passage 67 which communicates with horizontal branch passages 68 formed in the yoke member 43. The branch passages 68 in turn communicate with short downwardly disposed passages 69 formed in the tappet members 36.

Each of the valves 17 has a feed tube 71 disposed in its hollow stem 22, which feed tube extends substantially the length of the stem into the interior of the hollow valve head 21. The upper end of the tube 71 communicates directly with a passage 72 in the end of the valve stem, which terminates in axial alignment with the passage 69 of the tappet 36, and this end of the tube 71 is rigidly mounted in the stem 22, as by having a pressed fit with a contracted portion 73 of the bore of the stem. Below the contracted portion 73 of the stem 22, radial ducts 74 are provided, communicating with an annular space 75 within the stem and around the feed tube therein. It is hence obvious that cooling fluid from the branch passages 68 of the yoke member 33 will flow through the passages 69, 72, and tube 71

to the interior of the hollow valve head 21, where they absorb heat from this valve head and then pass upwardly through the annular space 75 and escape, by means of the ducts 74, into the space beneath the cover 15.

The operation of the oil pumping means will be readily understood. The metering slot 62 is formed of such a length and positioned in such a phase relation to the metering port 61 as to admit fluid under pressure from the interior of the hollow cam shaft 48 to the cylinder 42 beneath the plunger 41 through the connecting passages described, during that portion of the valve cycle in which the plunger 41 is moving upwardly, or is stationary. That is, fluid is admitted to the cylinder 42 during the period in which the valve 17 is closing and is closed. Upon downward movement of the plunger 41, the port 61 passes out of registry with the slot 62, cutting off the supply of oil to the cylinder 42 and acting as a valve to prevent back flow of the oil. On the down stroke of the plunger, which corresponds with the opening of the valve 17, the oil within the cylinder 42 is placed under pressure, which forces it to flow through the passages 67, 68 and 69 to the passage 72 of the valve stem, since no other path is available. From this point it passes downwardly through the feed tube 71 and upwardly through the annular space between the feed tube and the stem 22 in the manner already indicated.

It will be evident that by this invention a simple, direct and positive circulation of the cooling fluid through the engine valves is secured, and that this circulation is effected at the very period in the valve cycle when the valve is exposed to the greatest heat, that is, when the valve is open.

It will also be seen that all pumping losses caused by regurgitation in the valve cooling system are prevented in an efficient and simple manner by the use of the metering apertures as a non-return valve.

Furthermore, a simple and efficient means of conducting the cooling fluid from the stationary walls of supply to the rapidly moving valve is secured, and all interruption to flow of the fluid, and other evils that will be caused by a turning of the actuating yoke on its vertical axis are obviated.

It will be understood that various forms of the invention other than those described above may be used without departing from the spirit or scope of the invention.

What is claimed is:

1. The combination with an internal combustion engine having hollow valves, of means connecting said valves in pairs, and means associated with the connecting means for forcing cooling fluid through the valves.

2. The combination with an internal combustion engine having hollow valves, of

means for actuating said valves, and means associated with the actuating means for forcing cooling fluid through the valves.

3. In an internal combustion engine having pairs of hollow valves, actuating means connecting said pairs of valves, and pump means associated with the actuating means adapted to force cooling fluid through said valves.

4. In an internal combustion engine having hollow valves arranged in pairs, a yoke member connecting the stems of said valves to operate in unison, and pump means connected to the yoke member and operated thereby to force cooling fluid through the valves.

5. In a device for cooling the valves of internal combustion engines, a member adapted to actuate said valves, a plunger integral with the member, a cylindrical guide for the plunger, and means for conducting cooling fluid from the plunger to said valves.

6. In an internal combustion engine, the combination with valves having hollow stems, of a tube in each of said stems, means connecting said stems in pairs, a plunger on the connecting means, a cylinder adapted to receive the plunger, and means to reciprocate the said connecting means to operate the valves, whereby cooling oil is pumped by the plunger through said tubes.

7. In an internal combustion engine, hollow valves having hollow stems, a feed tube in each of the stems, actuating members for the valves having conduits communicating with the tubes, and pump means associated with the actuating members and operated thereby to circulate cooling fluid through said valves.

8. In an internal combustion engine, hollow valves having hollow stems, a tube in each of the stems, actuating members for the valves having conduits communicating with the tubes, and pump means integral with each actuating member and connected to the conduits to circulate cooling fluid through said valve.

9. In an internal combustion engine, pairs of hollow valves having hollow stems, an actuating yoke member for each pair of valves having conduits communicating with the stems, a hollow pump plunger integral with the yoke and communicating with the conduits, a cylinder in which the plunger is reciprocated by a yoke member, and means for admitting cooling fluid to the cylinder beneath the plunger during a portion of the valve cycle.

10. In an internal combustion engine having hollow valves, actuating means therefor having conduits connected to the valves and pump means adapted to circulate cooling fluid through the conduits to the valves, said pump means including a hollow plunger integral with the actuating means, a cylinder

for the plunger, and means for supplying a measured quantity of cooling fluid to the cylinder during the outstroke of the plunger.

11. In an internal combustion engine having a head, pairs of valves having parallel stems in the head, an actuating member associated with the stems of each pair of valves and guide means in the head between adjacent actuating members.

12. In an internal combustion engine, pairs of valves having parallel stems, a yoke member having adjacent tappets arranged between each pair of valves to actuate the stems, and means between adjacent yoke members to prevent rotation thereof.

13. In an internal combustion engine, pairs of valves having parallel stems, a yoke member having adjacent tappets arranged between each pair of valves to actuate the stems, and guide means between the adjacent yoke members to prevent rotation thereof.

14. In an internal combustion engine having hollow valves, actuating means for the valves including a hollow cam shaft adapted to contain cooling fluid under pressure and having metering ports, pumping means associated with the actuating means to circulate cooling fluid through the hollow valves, and means connecting the interior of the cam shaft to the pumping means during each revolution of said cam shaft.

15. In an internal combustion engine having hollow valves, actuating means for the valves including a hollow cam shaft adapted to contain cooling fluid under pressure and having metering ports, pumping means associated with the actuating means to circulate cooling fluid through the hollow valves, bearings for the cam shaft having metering slots connected to the pumping means and adapted to register with the metering ports during a portion of each revolution of the cam shaft.

16. In an internal combustion engine having hollow valves arranged in pairs, a yoke

member connecting the stems of the valves of each pair and having guide means including a cylinder and a plunger therein, a hollow cam shaft having cams adapted to 50 actuate the yoke members and connected to a source of cooling fluid under pressure, bearings for the cam shaft, and metering means for the cooling fluid including ports in the cam shaft and cooperating slots in 55 the bearings connected to the cylinders to admit cooling fluid beneath the plungers during that period in which the valves are closed.

17. In an internal combustion engine having hollow valves arranged in pairs, a yoke member connecting the stems of the valves of each pair and having guide means including a cylinder and a plunger therein, a hollow cam shaft having cams adapted to 60 actuate the yoke members and connected to a source of cooling fluid under pressure, bearings for the cam shaft, and means including ports in the cam shaft and communicating slots in the bearings adapted to 65 deliver a measured charge of cooling fluid to the cylinder when the plunger therein is on its outstroke, said means acting as a valve to prevent a return flow of the fluid on the return stroke of the plunger.

18. In an internal combustion engine having hollow valves arranged in pairs, a yoke member connecting the stems of the valves of each pair and having guide means including a cylinder and a plunger therein, a conduit in each plunger communicating with the hollow valves, a hollow cam shaft having cams adapted to actuate the yoke members and connected to a source of cooling fluid under pressure, bearings for the cam shaft, and means connecting the cylinder to the cam shaft during a portion of each revolution thereof, said means being adapted to prevent a return flow of the fluid on the return stroke of the plunger.

In testimony whereof I affix my signature.
LIONEL M. WOOLSON.
